CARRYING CASE FOR ELECTRIC HAND SAW AND OTHER PORTABLE TOOLS

Robert G. Platt, River Forest, Ill., assignor to
Century Display Mfg. Co., Inc., Chicago, Ill., a
corporation of Illinois

Application July 6, 1949, Serial No. 3,732

Term of patent 14 years

(Cl. D58—12)

To all whom it may concern:

Be it known that I, Robert G. Platt, a citizen of the United States, residing at River Forest, in the county of Cook and State of Illinois, have invented a new, original, and ornamental Design for a Carrying Case for Electric Hand Saw and Other Portable Tools, of which the following is a specification, reference being had to the accompanying drawing, forming part hereof.

In the drawings:

Figure 1 is an exploded perspective view of a carrying case for electric hand saw and other portable tools, showing my new design;

Figure 2 is a front elevational view of the carrying case of Figure 1 as it appears when assembled; and

Figure 3 is a side elevational view of the carrying case of Figure 2.

I claim:

The ornamental design for a carrying case for electric hand saw and other portable tools, as shown.

ROBERT G. PLATT.
